UNITED STATES PATENT OFFICE.

THOMAS W. FORSTER, OF DETROIT, MICHIGAN, ASSIGNOR OF ONE-HALF
TO BUHL STAMPING COMPANY, OF DETROIT, MICHIGAN.

CAN-CLOSURE.

No. 801,715.

Specification of Letters Patent.

Patented Oct. 10, 1905.

Application filed December 20, 1902. Serial No. 135,963.

To all whom it may concern:

Be it known that I, THOMAS W. FORSTER, a citizen of the United States, residing at Detroit, county of Wayne, State of Michigan, 5 have invented a certain new and useful Improvement in Can-Closures; and I declare the following to be a full, clear, and exact description of the invention, such as will enable others skilled in the art to which it pertains to 10 make and use the same, reference being had to the accompanying drawings, which form a part of this specification.

This invention relates to can-closures, and has for its object an improved can-closure that 15 is especially adapted for use with milk-cans.

The serious objection that has been found in the use of milk-cans closed by cap-like structures with a cavity on the under side of the cap arises from the separation of the cream 20 and the milk and the conversion of the cream into butter by the churning motion incident to the transportation of the can. One attempt that has been made to overcome the objection has introduced into the art the use of a wooden 25 plug, which overcame this source of objection, but introduced another objectionable feature incident to the character of the material employed for the closure, as a wooden plug cannot practically be kept clean, or so clean as is 30 requisite for use in milk-cans. The stopper or plug to be used must fit tightly to prevent the escape of the fluid and to prevent the introduction into the fluid of undesirable matter, especially such undesirable matter as rain- 35 water, where the can is exposed to a rain-storm. The cover must also be easily and readily removable from the can, and there should be no projecting part, especially no part which projects upward in a way to prevent 40 the stacking or piling up of empty cans on one another.

I have devised a form which contains none of the objectionable features mentioned and which overcomes the difficulties incident to 45 the hollow plug mentioned, and I show and describe the same herein.

In the drawings, Figure 1 is a sectional elevation of a plug in place in a can of small size. Fig. 2 is a perspective of the plug shown in 50 Fig. 1.

The main part of the plug is stamped and formed from a single and integral sheet of metal. It is dished or cup-shaped, with the cavity of the cup upward and with the bottom 55 or base of the cup arranged to engage in the

can with which the plug is used and with the cup-bottom in close proximity to the surface of the liquid contained in the can, and there are no seams to be at any time in contact with the liquid where such seam may receive and 60 retain portions of the liquid which becomes sour or tainted and from which the soured or tainted portions are with difficulty removed, or frequently not removed at all.

The plug 1 has integral side and bottom walls 65 2 and 3. The upper rim of the cup is rolled or beaded over a strengthening-wire 4, and this strengthening-wire 4 is preferably provided with a loop 5, that is bent outward from the circle of the wire and is arranged to engage a chain or other holding means 6. In the top of the cup is inserted and secured closure 7. This closure is also preferably cup-shaped but shallow, and the upper rim of the shallow cup which forms the closure is rolled 70 75 or beaded over the roll which terminates the upper edge of the larger cup. The entire plug is thus formed with a hollow or with an internal chamber entirely closed in and without seam or joint between the two parts which 80 form the plug except the joint which is at the extreme upper edge. The upper surface of the plug is sunk slightly below the extreme upper rim. To the upper surface of the sunken face of closure 7 is secured a rivet-plate 8 and 85 a ring 9, by means of which the plug is easily withdrawn from the can K, but which when not in use for the purpose of withdrawal drops into the cavity above the plate 7 and presents no part that projects above the rim. 90

What I claim is—

1. A closure for cans, comprising a deeply-concaved part and a shallowly-concaved part, a rim-wire over which the walls of both parts are beaded, the said rim-wire being provided with 95 a projecting loop, substantially as described.

2. In a can-closure, in combination with a deeply-concaved part to fit the can-neck, a shallowly-concaved part forming a closure to the top of the deeply-concaved part, means 100 for securing the two together and a lifting-ring secured to the shallowly-concaved part and adapted to lie in the cavity thereof, substantially as described.

In testimony whereof I sign this specification in the presence of two witnesses.

THOMAS W. FORSTER.
